UNITED STATES PATENT OFFICE.

SVEN T. NELSON, OF MICHIGAN CITY, INDIANA, ASSIGNOR TO SULLIVAN MACHINERY COMPANY, A CORPORATION OF MASSACHUSETTS.

FORGING MACHINE.

Application filed November 3, 1921. Serial No. 512,676.

My invention relates to forging machines, and more particularly to forging machines of the type adapted to form cutter bits for coal mining machines.

5 An object of my invention is to provide an improved forging machine. Another object of my invention is to provide an improved forging machine of the type adapted to form heated blanks into cutter bits for coal mining machines. A further object of my invention is to provide an improved forging machine which by a series of steps may operate upon a heated blank and form it into a shape appropriate for use as a coal mining 10 machine cutter bit. Other objects of my invention will hereinafter more fully appear.

In the accompanying drawings, I have shown for purposes of illustration, one form which my invention may assume in practice.

20 In these drawings,—

Figure 1 is a side elevation of a forging machine embodying my invention.

Fig. 2 is a front view thereof.

Fig. 3 is a view partially in elevation and 25 partially in vertical section on the line 3—3 of Fig. 2.

Fig. 4 is a transverse central section on the line 4—4 of Fig. 1.

Fig. 5 is a detail of construction.

30 In the illustrative embodiment of my improved forging machine I have shown it comprising a frame 1 in which is journaled upon a suitable shaft 2 a rotating bit carrying member 3 which cooperates with a series 35 of rotatable dies generally indicated at 4. The carrier member 3 is circular in periphery and is supported by a suitable web 5 upon a hub 6 secured to and rotatable with the shaft 2. The carrier member 3 is likewise provided with a series of blank receiving 40 slots 7 in which heated blanks are adapted to be dropped. These slots are rearwardly inclined and have arranged adjacent their rearward sides, speaking in terms of the direction of rotation, dies 8 inset in the periphery of the bit carrier and comprising surfaces 9 inclined to the direction of the slot 7 and adapted to give form to the front side 45 of the cutting end of the cutter bits. The heated blanks indicated in construction at 10 (Fig. 3) are adapted to be shoved into the slots 7 during the rotation of the carrier member 3 and the distance which they may be inserted is controlled by a pair of adjustable

55 semicircular blocks 11 disposed at opposite sides of the web 5 and adjustable relative thereto by means of oval slots 12 and holding bolts 13 which secure them to the sides of the frame 1. It will be understood, of course, that by reason of the fact that the block is 60 semicircular and that the periphery of the member 3 is semicircular, the block 11 and the member 3 can be concentric only in one position of the block and that the oval slotting permits very accurate adjustment. 65 However, when the block 11 is shifted below the center of rotation of the blank carrier the space between the surface of the block immediately above the axis and the inner wall of the rim of the blank carrier will be 70 greater than the space between the corresponding surfaces at a point in a horizontal plane passing through the axis. The result is that a blank inserted within the slot will gradually be fed outwardly as it travels 75 around to the horizontal plane above mentioned due to the decreased space between the block 11 and carrier. This provides an automatic feed for the blank as it travels into successive engagement with roller dies. 80

85 Mounted on shafts 14 which are journaled in sleeves 15, which latter are mounted in eccentrically bored bushings 16 disposed in a series of sockets in the frame 1, are rollers 17 which are provided at their peripheries with grooves 18 of a form to closely fit the sides of the die members 8 and to cooperate with them in the formation of the blanks to the desired shape. By reason of the eccentrical positioning of the sleeve 15 90 in the bushing 16, it will be evident that the position of the rollers may be varied relative to the shaft 2 and for the purpose of cooperating in the adjustment and locking of the bushings 16 in adjusted position, they are 95 provided with flanges 19 in which are formed a series of holes 20 adapted to cooperate with a series of differently spaced holes 21 in the side members of the frame 1 and machine screws or cap bolts 22 inserted 100 through the several holes 20 and 21 may serve to retain the bushings in their several adjusted positions. The shaft 2 is driven by means of a gear 23 secured thereto, which gear is driven by a smaller gear 24 carried 105 on a shaft 25. The latter is provided with a gear 26 meshing with a pinion 27 on a driving shaft 28 and the driving shaft 28 is

driven by a pulley wheel 29. After the bits have moved around beyond the last die 17 they are discharged by gravity to a chute 30 formed in frame 1.

From the foregoing description the mode of operation of this mechanism will be readily apparent. Let it be assumed that the member 11 is so adjusted relative to the member 3 that the exterior periphery of the member 11 is concentric with the periphery of the member 3. As a result of this construction heated blanks carried in the slots 7 will not have their relation to the inner end of the slots changed during rotation of the member 3. The bushings 16 will be adjusted in such manner as to bring the left hand or top roller 17 (Fig. 1) into a position such as to perform the first operation on the blank. The second or middle roller is adjusted slightly nearer the periphery of the member 3 and the third roller rolls substantially in contact therewith. As a result the three rollers will successively be engaged by a heated blank carried by the member 3 and will cooperate with the surfaces 9 in the forming of a bit having a point bent at an angle to the body of the bit and tapering from the body to the end of the point. It will also be evident that if the bushings 16 be adjusted to bring the axes of the dies 17 equidistant from the shaft 2, the blocks 11 may be lowered slightly and the bits will be progressively formed by the successive dies 17, as the bits will be protruded progressively further, by reason of the eccentricity of blocks 11, as they travel from a vertical to a horizontal position. Some variations in length of bits may be also secured by appropriate adjustments of blocks 11 and dies 17.

In the present device, two series of slots 7 and two series of rollers 17 are provided, but it will be evident that this number may be increased as desired, or, if desired, but a single series of rolls and slots need be employed. The insertion of the blanks is accomplished by shoving them in as the empty slots are approaching the first roller 17 and the blocks are automatically discharged by gravity as they pass below the horizontal line.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a tool forging machine, a relatively stationary die means for forming the lateral surfaces of a tool, a die for supporting the front face of the tool and adapted to interfit with said first mentioned die means, and

means for moving the supporting die relative to the stationary die whereby shaping of the cutting end of the tool is effected.

2. In a tool forging machine, a plurality of relatively stationary dies for forming the lateral surfaces of the tool, a die for supporting the front face of the tool and adapted to interfit with said stationary dies, and means for moving the supporting die in a path adjacent said stationary dies, the supporting die interfitting with each stationary die in succession.

3. A forging machine comprising a rotatable grooved forming die adapted to form the sides of the cutting portion of a blank, a second die having a raised portion adapted to extend within the groove of said other die to form said cutting portion, and means for causing relative curvilinear movement between said latter die and the axis of said rotatable die.

4. A forging machine comprising a rotatable grooved forming die adapted to form the sides of the cutting portion of a blank, a second die having a raised portion extending within the groove of said other die to form said cutting portion, and means for causing continuous relative curvilinear movement between said latter die and the axis of said rotatable die.

5. A forging machine comprising rotatable die means having sides, the conformation of which is substantially the same as that of the sides of the cutting portion of a bit formed thereby, a raised die having sides whose conformation is substantially the same as the sides of said rotatable die, and means whereby said dies are brought into operative relation to forge a blank and thereafter adapted to have a positive vertical separation therebetween.

6. A forging machine comprising a blank carrier, a raised die associated therewith, and a relatively stationary rotatable forming die having a groove into which extends said raised die to form the cutting face and sides of the cutting portion of a bit.

7. A forging machine comprising a blank carrier, a plurality of raised dies associated therewith, and a relatively stationary rotatable forming die having a groove into which extend said raised dies to form the cutting face and sides of the cutting portion of a bit.

8. A forging machine comprising a blank carrier, a plurality of raised dies associated therewith, and relatively stationary rotatable forming dies having a groove into which extend said raised dies to form the cutting face and sides of the cutting portion of a bit, said roller dies being adapted to perform successive degrees of forging on a blank.

9. A forging machine comprising a blank carrier, a plurality of raised dies associated therewith, and relatively stationary rotat-

able forming dies having a groove into which extend said raised dies to form the cutting face and sides of the cutting portion of a bit, one of said raised dies having 5 its longitudinal axis disposed in one plane and cooperating with one of said roller dies in said plane and another of said raised dies cooperating with another of said roller dies in another plane parallel to said first 10 mentioned plane.

10. In a tool forging machine, a relatively stationary die means for forming the lateral surfaces of a tool, a die which interfits with said stationary die means, means 15 for supporting the tool for engagement by said die during the forging operation, and means for moving the second die relative to the stationary die means.

11. A forging machine comprising a relatively stationary die means having sides the conformation of which is substantially the same as that of the sides of the cutting portion of a bit formed thereby, a relatively movable raised die having sides whose conformation is substantially complementary to 20 that of the sides of said stationary die means, and means for moving said raised die into operative relation with said stationary die to forge a blank.

12. In a tool forging machine, a blank carrier adapted to move a tool blank bodily in a fixed path and having means for supporting the blank at an acute angle relative to said path, and a relatively stationary die 25 means for forming the lateral surfaces of the blank, said relatively stationary die means being disposed for engagement by a blank moving in said carrier thereby to form the cutting portion of the tool with clearance.

13. In a forging machine, a blank carrier adapted to move a blank bodily in a fixed path and having means for supporting the blank at an acute angle relative to said path, a relatively stationary die means for forming the lateral surfaces of the blank, said relatively stationary die means being disposed for engagement by a blank moving in said carrier thereby to form the cutting portion of the bit with clearance, and means 30 for adjusting said die means to vary its effect on said blank.

14. In a tool forging machine, a blank carrier adapted to move a tool blank bodily in a fixed path and having means for supporting the blank at an acute angle relative to said path, and a series of relatively stationary die means for forming the lateral surfaces of the blank, said relatively stationary die means being disposed for successive engagement by a blank moving in said carrier thereby to form the cutting portion of the tool with clearance.

15. In a tool forging machine, a rotating blank carrier adapted to support a blank at

an acute angle relative to the path of travel thereof, and a relatively stationary die means for forming the lateral surfaces of the blank, said relatively stationary die means being disposed for engagement by a blank moving in said carrier thereby to form the cutting portion of the tool with clearance.

16. In a forging machine, a rotating blank carrier adapted to support a blank at an acute angle relative to the path of travel thereof, and a series of relatively stationary die means for forming the lateral surfaces of the blank, said relatively stationary die means being disposed for successive engagement by a blank moving in said carrier thereby to form the cutting portion of the bit with clearance.

17. In a cutter bit forging machine, a blank support, cutter bit forging die means, means for causing relative movement between said support and die means to effect a forging operation of the blank, and means for feeding a blank relative to the die means automatically during said relative movement.

18. In a cutter bit forging machine, a blank carrier, cutter bit forging die means, and means for automatically feeding a blank during the forging operation.

19. In a cutter bit forging machine, a blank carrier, cutter bit forging die means, and means automatically operative to effect feed of a blank carried in said blank carrier in the interval between the initiation of forging and the completion of the bit.

20. In a forging machine, a blank carrier adapted to move a blank bodily in a rotary path, means adjustable to move said blanks towards the periphery of said path during movement in said path, and die means for engaging a blank at different points in said path.

21. In a forging machine, a blank carrier adapted to move a blank bodily in a rotary path, means adjustable to move said blanks towards the periphery of said path during movement in said path, and die means for engaging a blank at different points in said path and adjustable towards and from said path.

22. In a cutter bit forging machine, a die carrier provided with a blank supporting die having blank engaging portions always relatively fixed and adapted to allow free feeding movement of the blank relative thereto during the forging operation, means for moving said carrier to cause said die to traverse a fixed path, and die means disposed for successive engagement by a blank moving in said path and cooperating with said supporting die in the formation of said blank to a desired shape.

23. In a cutter bit forging machine, a die carrier provided with an inclined slot for re-

- ceiving the shank of a bit blank and further having a die adapted to support the extremity of a blank during the forging operation, means for imparting movement to said die, and a plurality of die means disposed along the path of said die so as to be successively engaged by the bit blank being forged, said die means having converging die surfaces adapted to engage the sides of the bit and cooperating with said blank supporting die to impart an outward taper to the end of a blank, the inclination of said slot causing the longitudinal axis of a blank therein to make during forging by each of said die means an angle with the normal to its path at its points of contact with said die means.
24. In a cutter bit forging machine, a die carrier provided with a series of inclined slots for receiving the shanks of bit blanks and further having for each slot a die adapted to support the extremity of the respective blank during the forging operation, means for imparting orbital movement to said dies, and die means disposed along the orbit so as to be successively engaged by the bit blanks being forged, said die means having converging die surfaces adapted to engage the sides of the bit and cooperating with said blank supporting dies to impart an outward taper to the ends of said blanks, said die carrier being arranged to automatically discharge the finished bits from said slots before the orbit is completed.
25. In a forging machine, a die carrier provided with a plurality of series of raised blank supporting dies, means for moving said carrier to cause said dies to traverse fixed parallel paths, means for supporting each of said blanks at an acute angle relative to said path, and grooved die means disposed for successive engagement by blanks moving across said path and cooperating with said supporting dies in the formation of the sides of the cutting portion of said blanks and to forge clearance for the cutting portion of the bit.
26. In a forging machine, a blank carrier having means to engage the cutting faces of a plurality of blanks carried thereby, means to forge said blanks, means for normally causing relative curvilinear movement between said forging means and blanks, and means including a stationary element for controlling the position of said blanks relative to said forging dies.
27. A forging machine comprising a blank carrier having a raised die associated therewith to form the cutting portion of a bit, rotatable die means adapted to cooperate with said raised die to form said cutting portion, means for causing relative curvilinear movement between the axis of said rotatable forming means and said blank carrier, and means including a stationary element for controlling the position of the blank

along its longitudinal axis during the forging operation.

28. In a forging machine, a blank carrier, a raised die associated therewith, rotatable die means adapted to have interfitting relation with said raised die to form the cutting portion of a cutter bit, and rotatable means associated with said rotatable die for adjusting the disposition thereof with respect to said raised die to vary the degree of interfitting.

29. In a forging machine, a blank carrier, a raised die associated therewith, rotatable die means adapted to have interfitting relation with said raised die to form the cutting portion of a cutter bit, and means adjustable to effect a variation in the extent of interfitting of said die and die means, said adjustable means having throughout a forging operation a fixed adjusted position.

30. In a cutter bit forging machine, a bit blank carrier, a grooved rotatable forming die to forge the cutting portion of a blank carried by said carrier, means for supporting said blank by said carrier whereby the cutting portion is forged with clearance, means for causing relative curvilinear movement between said rotatable die and blank, and means adapted to abut the end of a blank during the forging operation.

31. In a forging machine, a blank carrier, a grooved rotatable forming die to forge the cutting portion of a blank carrier thereby, means for supporting said blank by said carrier whereby the cutting portion is forged with clearance, means for causing relative curvilinear movement between said rotatable die and blank, and means including a stationary element adapted to abut the end of a blank during the forging operation and to automatically disengage the same when the forging operation is completed.

32. In a forging machine, a blank carrier adapted to move along a fixed path, dies to forge blanks carried by said carrier, and means adapted to be movable independently of said carrier for engaging one end of said blanks.

33. In a forging machine, a rotary blank carrier, dies to forge the blanks, one of said dies having a projecting surface adapted to project into a recess in another die, said dies being arranged at predetermined distances from the center of rotation of said carrier, and means to adjust the position of the blanks away from the center of rotation of said carrier.

34. In a forging machine, a blank carrier movable along a fixed path, dies to forge blanks carried by said carrier, and a member for adjusting the position of the blanks having a fixed position relative to said carrier.

35. In a forging machine, a blank carrier movable along a fixed path, dies to forge

blanks carried by said carrier, and a member for adjusting the position of the blanks carried by said carrier, said member including a segment and means for holding the same in its different operative positions.

36. In a forging machine, a rotatable blank carrier having a plurality of axially spaced blank receiving means, blank adjusting means acting to effect longitudinal adjustment of the blanks carried thereby, and die means for forging said blanks.

37. In a forging machine, a rotatable blank carrier having a plurality of axially spaced blank receiving means, blank adjusting means projecting axially inwardly of said carrier, and axially spaced rotatable die means for forging said blanks.

38. In a forging machine, a rotatable blank carrier having a plurality of axially spaced blank receiving means, blank adjusting means projecting axially inwardly of said carrier, and die means for forging said blanks.

39. In a forging machine, a rotatable blank carrier having a plurality of axially spaced blank receiving means and recesses, blank adjusting means disposed in the recesses in said carrier, and die means for forging said blanks.

40. In a forging machine, a supporting frame, a rotatable blank carrier mounted thereon, said carrier having blank receiving means, blank adjusting means mounted on said frame for adjusting the blanks in said blank receiving means, and die means for forging said blanks.

41. In a forging machine, a supporting frame, a rotatable blank carrier mounted on said frame and having an annular recess therein, said carrier having blank receiving means communicating with said recess, blank adjusting means mounted on said frame and projecting into said recess and beneath said blank receiving means, and die means for forging said blanks.

42. In a forging machine, means for supporting blanks during forging providing a plurality of blank receiving means each having a raised die associated therewith disposed in a plurality of planes, forging die means for forging the blanks disposed in said receiving means, said die means having grooves into which said raised dies are adapted to extend, and means for effecting relative movement between said raised dies and said die means.

43. In a forging machine, means for supporting blanks during forging providing a plurality of blank receiving means each hav-

ing a raised die associated therewith, certain of said dies being disposed in parallel planes, and roller dies having grooves into which extend said raised dies for forging blanks disposed in said receiving means.

44. In a forging machine, means for supporting blanks during forging providing a plurality of blank receiving means each having a raised die associated therewith, and means including a roller die having a groove into which said raised dies are adapted to extend for forging simultaneously to the same degree a plurality of blanks disposed in said receiving means.

45. In a forging machine, means for supporting blanks during forging providing a plurality of blank receiving means each having a raised die associated therewith, means for forging a plurality of blanks disposed in said receiving means, said forging means including a plurality of grooved roller dies for performing the same degree of forging on each of said blanks, said raised dies being adapted to extend within the grooves in said roller dies, and means for effecting relative movement between said raised dies and said roller die.

46. In a forging machine, means for supporting blanks during forging providing a plurality of blank receiving means each having a raised die associated therewith of substantially the same cross section as the cutting portion of the bit formed thereby, said dies being disposed in a plurality of planes, and die means operating on blanks therein including a plurality of rotatable dies each having a groove to cooperate with a raised die.

47. A forging machine for forming the cutting ends of cutter bits comprising a die against which the front face of the bit portion is to be formed, die means including a plurality of grooved dies for forming the other surfaces of the cutting end, and means for causing relative movement between said die and die means to effect forming of said cutting ends.

48. A forging machine for forming the cutting ends of cutter bits comprising a die against which the front face of the bit portion is to be formed, die means including a plurality of grooved dies for forming the other surfaces of the cutting end, each of said plurality of dies successively operating upon a single blank, and means for causing relative movement between said die and die means to effect forming of said cutting ends.

In testimony whereof I affix my signature.
SVEN T. NELSON.
